VEHICLE JACK SYSTEM

Walter C. Cranston, Worcester, Mass.

Application January 30, 1933, Serial No. 654,222

4 Claims. (Cl. 254—86)

This invention relates to a system of jacks carried by an automobile or other vehicle for lifting the same and to means for connecting these jacks with the motive power which the vehicle carries for operating them.

The principal objects of the invention are to provide a simple and practical way for connecting four permanent separate jacks with the vehicle in such a way that they will operate by moving downward to lift their respective corners of the vehicle; to provide a simple and practical means whereby the power from the motor can be connected with any one of these jacks at a time to operate the jack to lift its part of the vehicle or to reverse it and withdraw it to the position it has to assume when the jack is not being used; to provide a control for the jacks located within reach of the driver indicating the four jacks respectively and showing when the mechanism is moved to a position to operate any one of the particular jacks, and to provide a simple means for making the shift to connect the operating power with any one of the jacks. The invention also involves details of each one of these features.

Other objects and advantages of the invention will appear hereinafter.

Reference is to be had to the accompanying drawings, in which

Fig. 1 is a plan of the running gear of an automobile showing a preferred location of the jacks and the flexible shafts for driving them;

Fig. 2 is an elevation, partly in section, showing the position of the controlling means on the dash and the transmission as well as the connection of the two;

Fig. 3 is an end view as indicated by the arrow 3 in Fig. 2;

Fig. 4 is a sectional view on an inclined line 4—4 of Fig. 3;

Fig. 5 is a sectional view on the line 5—5 of Fig. 4;

Fig. 6 is an elevation of the controlling lever and associated parts as indicated by the arrow 6 in Fig. 2;

Fig. 7 is a side view, partly in section, of means for connecting each one of the individual flexible shafts going to the jacks with the means for driving them;

Fig. 8 is an end view, taken in the direction of the arrow 8 in Fig. 7;

Fig. 9 is a sectional view on the inclined line 9—9 of Fig. 7;

Fig. 10 is an elevation on an inclined plane as indicated by the arrow 10 in Fig. 7;

Fig. 11 is a sectional view on the line 11—11 of Fig. 9;

Fig. 12 is an elevation of part of the frame of the car showing one of the jacks in diametrical section, and

Fig. 13 is a sectional view of the jack on the line 13—13 in Fig. 12.

As is well known, there has been a great deal of difficulty about the use of jacks on automobiles, particularly the heavier ones like trucks and busses, and several schemes have been proposed for carrying four jacks on the car and operating them by power so as to control the operation of the jacks and the lifting of the car. By this invention the jacks are operated individually and the changing of the operation from one jack to another is reduced to its simplest terms. The jacks are operated by power connected with the transmission in a very simple way so as to provide for forward drive of the jacks and reverse and the jacks are located permanently on the car and firmly mounted so that they do not readily get out of order by the vibration to which they are subjected and they are made in a very simple form involving a minimum of expense and repair.

The motor of the car is not shown but it drives a shaft 10 from the motor shaft 9 as usual having a gear 11. The usual countershaft gear 12 and reverse idler gear 13 are connected in a well-known way. It is from these two gears 12 and 13 which, meshing together, must rotate in opposite directions that the jacks are driven according to this invention.

For the purpose of transmitting the power in either direction from these two gears 12 and 13, a pinion 14 is provided mounted on a frame 15 fixed on a shaft 16. This pinion is fixed on a rotatable stud 17 carried by the frame 15 and connected with a flexible shaft 18. The casing 19 in which these parts are located is usually provided on a car but it has to be provided with an additional cap 20 in which the gear 14 is located. This cap is provided with an arcuate slot 21 in which the stud 17 and associated parts travel. Obviously this frame 15 can be swung around so that the pinion 14 will mesh with either of the gears 12 or 13. In one position it will be rotated in one direction and of course in the other position it will be rotated in the other direction.

The shaft 16 is operated by an arm 22 from an operating lever 23 on the dash. This operating lever works in a slot 24 and is shown in Fig. 6 in neutral position. Obviously it can be moved up or down and a slot 24 in the plate 25 is marked

110

to show which position it should be put in for lifting the car and for letting it down. The lever 23 is connected with an adjustable rod 26. This rod is connected by an L-shaped bar 27 with the 5 arm 22 and works against the opposition of a spring 28. The angular end on the bar 27 and arm 22 constitute a bell crank fixed to the shaft 16. It will be seen therefore that by these means 10 the power is transmitted in either direction from the motor to the shaft 18.

The shaft 18 passes to a casing 30 and is provided with a gear or pinion 31 in the casing pivoted on an arm 32 which is centered on an axis at the center of the casing and connected by a 15 universal joint 34 with a rod 35 raised by a spring 36 into the position shown in Fig. 7. On the end of this rod is a pointer 38 located on the dash or footboard of the car. This pointer has a pin 39 adapted to enter in one of four recesses 40 provided in a stationary part through which the shaft 35 passes. Under this pointer is a plate 41 having four designations on it for showing which one of the jacks the device is connected to for operating. It is shown in Fig. 8 in neutral position and in Fig. 7 in active position. When the pointer is pulled out and turned so that the pin 39 can be forced by the spring 36 into one of the holes 40, the gear 31 is necessarily turned to one of the four operative positions, that is, it is turned 20 from the position shown in Fig. 9 into mesh with one of four gears 42. These four gears are each connected by a friction means, as a clutch 60, with a separate flexible shaft 43 and when the parts are in the position just described, one of 25 these jacks will be operated by power through the train of gearing described. The friction connection is desirable to avoid injury to the jack. The casing 30 is provided with an arcuate slot 44 for receiving the shaft 18. This slot does not necessarily extend much beyond three-quarters of a 30 circle, as shown in Fig. 10. As stated, each one of the shafts 43 is connected with a separate jack.

Each of these jacks is provided with a worm 45, each worm being connected with its respective 45 flexible shaft and each worm meshing with a worm wheel 46. Fixed to this worm wheel is an interior screw 47 which operates a nut 48 having a hollow unthreaded shank 49 which at the other end of the jack is provided with an external nut 50 meshing with an internal screw 51. This internal 50 screw is connected with a base 52 of the jack and is contained in a casing 53 which is fixed to the axle 54 or other stationary part of the automobile frame or chassis. Ball bearings 55 are shown at the top of the jack under a cap 56 which completes the jack casing. Obviously the turning of the worm in one direction will expand the jack and move the nut 48 down to the bottom, carrying with it the internal screw 51, and when the nut 48 engages a collar 57 on the bottom of the screw 47, the nut 50 will have to rotate and carry down the internal screw 51. Thus we have a double expansion jack capable of lifting a car of any size and with tires of the largest diameter. This jack is of a solid sturdy construction and can be attached to the vehicle in a positive and permanent manner, has no pawls or other relatively movable parts that are likely to get out of order, because it is reversed simply by reversing the direction of rotation of the worm 45. It does not depend on any pivoted or spring-pressed means for reversing it or for holding it in its forward or reversed position.

This whole construction is compact, mechanical and strong. No material force is brought to

bear on any part that is weak or apt to give away in practice, the parts are all practically jar and vibration-proof, the parts start into operation practically instantaneously, are reversed without trouble, and they are all fixedly secured in position. The invention constitutes a substitute for the loose jack ordinarily used, the power is obtained from the engine without the addition of a power-plant or any new connections to the battery, and it is an extremely serviceable mechanism all the way through and very convenient to handle and manipulate. On the end of each worm 45 is a square extension 61 so that each jack can be operated manually.

Although I have illustrated and described only one form of my invention, I am aware of the fact that modifications can be made therein by any person skilled in the art without departing from the scope of the invention as expressed in the claims. Therefore I do not wish to be limited to all the details of construction herein shown and described, but what I do claim is:

1. In an automobile, the combination with a power-driven shaft having a gear thereon, a reverse idler gear meshing therewith, and a counter-shaft gear meshing with the idler gear, of a swinging frame, a rotary shaft on said frame, a pinion on the second shaft adapted to be brought into mesh with either one of the two last-named gears to rotate the pinion in either direction, a flexible shaft fixed to the pinion, an arm fixed to said frame, an operating lever located at the front of the car and connected with said arm for operating it and the frame, a gear fixed with respect to said flexible shaft, a plurality of gears with any one of which the gear on said flexible shaft is adapted to be brought into mesh, and a plurality of jacks, each connected with one of the other gears to be operated thereby.

2. In an automobile, the combination with a power-driven shaft having a gear thereon, a reverse idler gear meshing therewith, and a counter-shaft gear meshing with the idler gear, of a swinging frame, a rotary shaft on said frame, a pinion on the second shaft adapted to be brought into mesh with either one of the two last-named gears to rotate the pinion in either direction, a flexible shaft fixed to the pinion, an arm fixed to said frame, an operating lever located at the front of the car and connected with said arm for operating it, means for indicating the position of the controlling lever and therefore the position of the pinion and the direction of rotation of the shaft, a casing, a gear in the casing fixed with respect to said flexible shaft, a support for the last-named gear movable in the casing, a plurality of gears in the casing with any one of which the gear or the shaft is adapted to be brought into mesh, and a plurality of jacks, each connected with one of the other gears in the casing to be operated thereby.

3. In an automobile, the combination of a movable pinion, means connected with the power generating apparatus of the car for rotating said pinion in one direction when it is in one of two extreme positions and in the other direction when in the other extreme position, a shaft on which the pinion is mounted, a gear connected with the shaft to be driven thereby, a frame on which the last-named gear is eccentrically mounted, said frame being mounted to swing on a stationary axis, a series of gears at equal distances from the point at which said frame is pivoted, a jack connected with each one of the last-named gears.

to be operated thereby, and means for turning said frame to bring the first-named gear into mesh with any one of the other gears to enable any one of the jacks to be operated at will.

5 4. In an automobile jack operating mechanism, the combination of a plurality of jacks, a series of gears equally spaced around a center, a frame pivoted to swing on said center, a gear carried by said frame in position to mesh with any one

of said gears as the frame is swung around, means connected with the power mechanism of the automobile for rotating the last-named gear in either direction irrespective of its position, a rod connected with said frame for turning it, a pointer fixed to the rod, and an indicating plate showing which one of the gears, and therefore which one of the jacks, is connected with the power. 80
